When monoalkylamines, dialkylamines, monoalkenylamines, or dialkenylamines having 11 to 18 carbon atoms in the hydrocarbon chain or chains are reacted in equimolecular amounts with lower alkanoic acids and cyanamide in the absence of solvents and at a temperature high enough to keep the mixture molten, but not much higher than 170°C., the expected substituted guanidine salts are formed quickly in yields of 90 percent or better. Impurities, such as iron ions, do not interfere and no pH adjustment is needed.

PROCESS FOR PREPARING SALTS OF ALKYL AND ALKENYLGUANIDINES

The present invention relates to a process for preparing alkyl- and alkenyl-guanidine salts from alkylamines, aliphatic carboxylic acids, and cyanamide.

In U. S. Pat. specification No. 3,004,065, there is described a process for preparing alkyl-guanidine salts in aqueous solution from alkylamines containing more than 10 carbon atoms in the alkyl radical, salts of these amines, cyanamide and the acids which provide the anionic moiety of the amine salts. The reaction conditions include a temperature of 95° to 100° C. and a pH value of at least 9. In this process, it is important for achieving an acceptable yield that the cyanamide solution used be free of ferric ions. Even so, there is achieved a maximum yield of only 80 percent, based on the amount of amine used, or of 52 percent, based on the amount of cyanamide used, there being employed a considerable excess of cyanamide, as well as an excess of acid over the amine used. A particular disadvantage of this known process is the long period of reaction, typically 3.5 hours.

Furthermore, from U. S. Pat. specification No. 3,383,408, there is known a process for preparing alkyl-guanidine salts from alkylamines, carboxylic acids, and an aqueous cyanamide solution in which the starting materials are reacted in substantially equimolar amounts at a temperature of about 70°-150° C. The period of reaction in this process is as much as 5 hours and the obtained yields of 31.5 - 73 percent are also unsatisfactory.

The object of the present invention is an economical, simple process of preparing alkyl- or alkenyl-guanidine salts from the corresponding amines, aliphatic carboxylic acids, and cyanamide, which process overcomes the above-mentioned disadvantages of the known processes.

According to the present invention, alkyl- and alkenyl-guanidine salts are prepared from alkylamines or alkenyl-amines containing more than 10 carbon atoms in a hydrocarbon radical, aliphatic carboxylic acids, which preferably contain up to 5 carbon atoms, and cyanamide in substantially equimolecular amounts at a temperature of 80°-170° C., preferably of 100°-150° C., without the use of a solvent, in a melt within a period of 3-30 minutes.

The cyanamide may be used as a solid or as an aqueous solution or slurry containing more than 50 percent cyanamide. When a cyanamide solution or slurry is used, it is necessary to prevent substantial amounts of water from entering the melt. According to a preferred embodiment of the process according to the present invention, the cyanamide solution or slurry is added under conditions under which the water evaporates immediately. Solid cyanamide is added to the amine salt melt preferably before the melt has reached the reaction temperature so that the reaction components are well mixed when the reaction begins.

The period during which the reactants are kept at the reaction temperature must be controlled carefully. If it is less than 3 minutes, the reaction is incomplete. When the period of heating exceeds 30 minutes, a significant amount of the guanidine formed decomposes. Longer periods of reaction are used when the cyanamide is added in the form of a solution than with cyanamide in solid form.

The reaction temperature and optimum reaction period are inversely related. Reaction temperatures between 100° and 150° C. are preferred, and the reaction mixture must be molten at the chosen temperature.

The starting materials are used in equimolecular amounts. The yields which can be achieved by means of the process according to the present invention are between 90 and 96 percent, based on the amounts of amine or cyanamide employed as starting materials. Surprisingly, we have found that the yield is generally reduced by the amount by which the reactants exceed the molar ratio. Thus, if an excess of cyanamide or of acid is used, the degree of conversion of the amine is decreased and not increased.

If desired, the process according to the present invention can be carried out continuously, for example, in a flow-through tube.

It is a particular advantage of the process according to the present invention that the pH value of the melt and the purity of the starting materials are not critical. Thus, ferric ions present in the cyanamide do not exert an undesirable influence on the course of the reaction.

Products obtained by the process according to the present invention can be used as algicides, fungicides, or wetting agents, as is known in itself.

The following Examples further illustrate the present invention. All parts are by weight unless stated otherwise.

EXAMPLE 1

Into an open vessel equipped with a stirrer and a heating or cooling jacket, there were placed 50 parts dodecylamine and 16.2 parts glacial acetic acid. The dodecylamine acetate formed after mixing was melted at 70° C., and 12.2 parts cyanamide (95 percent) were introduced. The mole ratio of dodecylamine:acetic acid:cyanamide was 1:1:1. Heating was continued until the reaction mixture reached 100°-105° C. The temperature slowly increased spontaneously thereafter due to the exothermic reaction. From 130° C., the reaction mixture was cooled to 115° C. The total reaction time was 5 minutes. Thereafter, the melt, which was not very viscous, was discharged and permitted to solidify in crystalline form. It contained 90.0 percent dodecyl-guanidine acetate. Thus, the yield was 90 percent, calculated on the dodecylamine or on the cyanamide used.

Example 2

As described in Example 1, 50 parts of dodecylamine were melted with 20 parts propionic acid, and 11.9 parts 97 percent cyanamide, mixed with 1.2 parts water, were introduced at 80°C. The reaction proceeded exothermically from 105°C. to 130°C., and the reaction mixture was subsequently held at 110°C. The total reaction time was 30 minutes. 82.2 Parts of a crystalline product containing 89.7 percent dodecyl-guanidine propionate were obtained. The yield was 90.0 percent, calculated on the dodecylamine or on the cyanamide used.

Example 3

50 Parts dodecylamine were heated in a closed vessel with 16.2 parts glacial acetic acid to 110°-115°C. and

11.8 parts cyanamide were added dropwise at this temperature over a period of 10 minutes in the form of a 50 percent solution in water. During the addition of the cyanamide solution, the reaction mixture was heated to 130°C. while the vacuum of a water jet pump was applied, and thereafter again cooled to 115°C. The reaction time, after the last addition of cyanamide, was 15 minutes. There were obtained 78.6 parts of melt containing 88.5 percent dodecyl-guanidine acetate, corresponding to a yield of 89.5 percent, calculated on the dodecylamine or on the cyanamide used.

Example 4

50 Parts oleylamine were melted with 11.2 parts glacial acetic acid at 90° -95°C., 8.0 parts 98 percent cyanamide were introduced and the mixture was heated to 130°C. After a total reaction time of 15 minutes, the honey-colored melt was discharged from the reaction vessel and solidified in crystalline form. There were obtained 69.2 parts of a product containing 91.2 percent oleyl-guanidine acetate.

Example 5

50 Parts distearylamine were melted with 5.75 parts glacial acetic acid at 100°C. and thereafter 4.1 parts 98 percent cyanamide were introduced. The reaction mixture was heated to 130° -140°C., only a very weakly exothermic reaction taking place. For completion of the reaction, the reaction mixture was further heated to 150°C. since the melt began to solidify at 140°C. After a total reaction time of 15 minutes, there were obtained 59.9 parts by weight of distearyl-guanidine acetate having a purity of 96.1 percent. The yield was 96 percent, calculated on the amine or cyanamide used.

Example 6

50 Parts oleylamine were mixed with 8.6 parts 100 percent formic acid, and 8.0 parts 98 cyanamide were introduced at 90°C. The reaction proceeded with slight foaming at increasing temperature. At 130°C., the temperature increase was broken off by cooling, and the melt was maintained at 110° -115°C. for 12 minutes. There were obtained 66.6 parts of a product having the consistency of a paste and containing 75 percent oleyl-

guanidine formate. The purity was the same as the yield because the components were used in a mole ratio of 1:1.

Example 7

50 Parts oleylamine were melted with 13.9 parts propionic acid (99 percent), and 8.0 parts 98 percent cyanamide were mixed in at 85°C. The temperature of the reaction mixture was brought to 130°C. by heating, 10 because the reaction was less vigorous than with formic or acetic acid, and subsequently maintained for 10 minutes at 115°C. Upon cooling, the product solidified to 7.18 parts of a wax-like mass containing 91.6 percent oleyl-guanidine propionate. The yield, therefore, 15 was 91.6 percent based on any one of the starting materials.

What is claimed is:

1. A process for preparing an alkyl or alkenyl-guanidine salt which comprises reacting equimolecular amounts of a monoalkylamine, dialkylamine, monoalkenylamine or dialkenylamine having from 11 to 18 carbon atoms in the hydrocarbon chain, of a lower alkanoic acid, and of cyanamide in the absence of solvent at a temperature sufficient to keep the reaction mixture molten but no higher than 170°C until said alkyl- or alkenyl-guanidine salt is formed, but not longer than 30 minutes.
2. A process as set forth in claim 1, wherein said aliphatic amine and said alkanoic acid are combined 20 prior to said reacting, and the cyanamide is added thereafter to the product so obtained.
3. A process as set forth in claim 2, wherein said cyanamide is added to said product in the form of an aqueous slurry or solution containing more than 50 percent of said cyanamide under conditions causing substantially complete evaporation of the water in said slurry or solution prior to said reacting.

4. A process as set forth in claim 2, wherein said cyanamide is added to said product in the solid state at a temperature lower than the temperature required for reacting said cyanamide with said product.

5. A process as set forth in claim 1, wherein said temperature is between 100° and 150°C.

6. A process as set forth in claim 1, said temperature 45 being at least 80°C.
